UNITED STATES PATENT OFFICE

132,872

DESIGN FOR AN AIR STERILIZING LAMP FIXTURE OR THE LIKE

Meyer B. Cherniak, New York, N. Y.

Application June 28, 1941, Serial No. 101,795

Term of patent 7 years

To all whom it may concern:

Be it known that I, Meyer B. Cherniak, a citizen of the United States, residing at 22 West 27th Street, New York city, in the county and State of New York, have invented a new, original, and ornamental Design for an Air Sterilizing Lamp Fixture or the like, of which the following is a specification, reference being had to the accompanying drawing, forming part thereof, and in which:

Figure 1 is a front elevational view of an air

sterilizing lamp fixture or the like, showing my new design.

Figure 2 is a top plan view of the same.

Figure 3 is an end elevational view thereof.

Figure 4 is a bottom plan view thereof; and

Figure 5 is a cross-sectional view taken on the line 5—5 in Figure 1.

I claim:

The ornamental design for an air sterilizing lamp fixture or the like, substantially as shown.

MEYER B. CHERNIAK,
